UNITED STATES PATENT OFFICE.

JAY C. TRUESDELL, OF JAMAICA, NEW YORK, ASSIGNOR TO GEORGE O. GRIDLEY,
OF SPRINGFIELD, MASSACHUSETTS.

CAN OPENER.

Application filed March 16, 1923. Serial No. 625,496.

To all whom it may concern:

Be it known that I, JAY C. TRUESDELL, a citizen of the United States, residing at Jamaica, in the county of Queens and State of New York, have invented certain new and useful Improvements in Can Openers; and I do hereby declare the following to be a full, clear, and exact description of the invention, such as will enable others skilled in the art to which it appertains to make and use the same.

The present invention relates to devices for cutting sheet metal articles and more particularly to such devices employed for opening sealed metallic containers by severing a portion from the container.

The object of the present invention is to provide a new and improved form of can opener which will cut the can rapidly and easily and in such a manner that the resultant opening is substantially co-extensive with the inner area of the can.

With this object in view one feature of the invention contemplates the provision of a cutting member adapted to enter the side wall of the container in proximity to the top, together with means for engaging and gripping the container along the junction of the top and side wall to hold the can and permit relative movement of the can and cutting member and sever the can top.

A further feature of the invention contemplates the provision of two jointed members, one of the members being provided with cooperating gripping devices to engage and grip the can and the second member being provided with a cutting device which is adapted to enter upon movement of the two parts of the member into alinement and to sever the can upon a relative bodily movement of the two jointed members.

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention Fig. 1 represents a plan view of the improved can opener in operative position upon a can; Fig. 2 is a detail illustrating a view of the cutting member and support taken along the line 2—2 of Fig. 1; Fig. 3 is a

similar view of the gripping members and support taken along the line 3—3 of Fig. 1; Fig. 4 is a detail illustrating one of the gripping members; and Fig. 5 is a detail illustrating the cutting knife.

The can opener shown in the illustrated embodiment of the invention is particularly adapted for opening the conventional form of can by a complete removal of the top. This is accomplished through the provision of two jointed members pivoted together at one end and adapted to progressively cut the wall of the can through relative movements of the jointed members toward and from one another. One of the jointed members is provided with cooperating gripping devices adapted to engage and grip the edge of the can top upon movement of the two portions of the member into alinement and the second member is provided with a cutting blade mounted upon one part which is caused to pierce the wall of the can below the top upon movement of the two parts of the member into substantial alinement. After the two parts of the jointed members have been moved into substantial alinement, as indicated in Fig. 1, a relative movement of the members toward one another progressively cuts the wall of the can below the top. Thereafter the members may be separated to engage with the can at a new point and again brought together to continue the cutting, this operation being repeated until the can top has been substantially completely severed from the body. It will be evident that by severing the top in this manner an opening is provided substantially co-extensive with the interior area of the can which permits the contents of the can to be emptied intact. Furthermore the arrangement of the cutting edge is such that the wall of the can along the edge of the cut is turned outwardly, leaving a smooth opening free from sharp or ragged edges which would tend to obstruct the emptying of the can.

Upon referring to Fig. 1, it will be observed that the can opener comprises two jointed members indicated generally at 10 and 11, which are pivotally connected at 14. The member 10 comprises a stamping 16 having pivot receiving openings 18 and 19 formed in opposite ends and having an integral lug 20 intermediate the ends, which constitutes one of the cooperating gripper

members. A second stamping 22 is provided with a handle portion 24 and with a lug 26 which cooperates with the lug 20 to form the complete gripping device. It will be observed that the gripping face 28 of the lug 26 is longer than the face of the lug 20 in order to project downwardly along the side of the can, the gripping face of the lug 20 being adapted to engage with the inner side of the bead formed at the junction of the top and side wall. The stampings forming the two parts of the member 10 are pivotally connected at 30 in such a manner that movement of the two parts into substantial alinement closes the cooperating gripping jaws and rigidly clamps the bead 32. The member 11 comprises a stamping 40 and a second stamping 42 having a handle portion 44 and provided adjacent the pivot connection 46 with a cutting blade 48. This cutting blade, as indicated in Figs. 1 and 5, is provided with a pointed end 50 and a cutting edge 52, the blade being arranged in such a manner that movement of the two portions of the member 11 into alinement causes the pointed end 50 of the cutting blade to initially pierce the side wall of the can below the top and project into the can in substantially the manner shown in dotted lines in Fig. 1. With the two gripping members engaging and clamping the bead upon the top of the can and the cutting member projecting within the wall of the can as indicated a relative bodily movement of the two members about the pivot 14 severs the side wall of the can below the top. Thereafter the members are separated to cause the gripping devices to engage with the can at an advance point and again brought together to continue the cut, this operation being repeated until the cut has progressed about the entire periphery of the

can. It will be obvious that with this construction the can top is severed by a series of scissors-like movements progressing about the top. The position of the can opener as a whole remains substantially stationary and the can is bodily revolved through the movements of the member 10 toward the member 11. From an inspection of Fig. 1 it will be observed that the cutting edge 52 is inclined with respect to that portion of the can engaged thereby so that the wall of the can is cut by a sheering movement and in addition is turned outwardly, forming a smooth inner surface.

I claim:—

1. An apparatus of the class described comprising two jointed levers pivoted together adjacent their inner ends, cooperating gripping members carried by one of the levers and adapted to engage a container at the junction of the top and side wall, and a cutting blade carried by the cooperating lever and adapted to pierce the side wall of the container below the top upon movement of the two parts of the lever into alinement and to sever the side wall upon relative bodily movement of the levers about the pivotal connection.

2. An apparatus of the class described comprising a two-part member, a gripping device carried by each part of the member, the gripping devices being adapted to engage a container upon movement of the two parts of the lever into alinement, a second two-part member pivotally connected to the first member, and a cutting blade carried by one part of the member and adapted to be forced through the wall of the container upon movement of the two parts of the member into alinement.

JAY C. TRUESDELL.
